(57) **CLAIM**

The ornamental design for an attachment for a male dog housebreaking pad as shown and described.

DESCRIPTION

FIG. 1 is a top, left perspective view of a first embodiment of an attachment for a male dog housebreaking pad, depicting my new design;

FIG. 2 is a front view of the attachment for a male dog housebreaking pad thereof;

FIG. 3 is a rear view of the attachment for a male dog housebreaking pad thereof;

FIG. 4 is a left side view of the attachment for a male dog housebreaking pad thereof;

FIG. 5 is a right side view of the attachment for a male dog housebreaking pad thereof;

FIG. 6 is a top view of the attachment for a male dog housebreaking pad thereof;

FIG. 7 is a bottom view of the attachment for a male dog housebreaking pad thereof; and

FIG. 8 is a perspective view of the attachment for a male dog housebreaking pad thereof, shown in an environment of use attached to a housebreaking pad used by a dog;

FIG. 9 is a top, left perspective view of a second embodiment of an attachment for a male dog housebreaking pad, depicting my new design;

FIG. 10 is a front view of the attachment for a male dog housebreaking pad thereof;

FIG. 11 is a rear view of the attachment for a male dog housebreaking pad thereof;

FIG. 12 is a left side view of the attachment for a male dog housebreaking pad thereof;

FIG. 13 is a right side view of the attachment for a male dog housebreaking pad thereof;

FIG. 14 is a top view of the attachment for a male dog housebreaking pad thereof;

FIG. 15 is a bottom view of the attachment for a male dog housebreaking pad thereof;

(Continued)

FIG. 16 is a perspective view of the attachment for a male dog housebreaking pad of FIG. 9, shown in an environment of use attached to a housebreaking pad used by a dog; and, FIG. 17 is a perspective view of the attachment for a male dog housebreaking pad of FIG. 9, prior to assembly.

The broken line showing of a housebreaking pad and a dog in FIGS. 8 and 16 depicts the environment of the attachment for a male dog housebreaking pad and forms no part of the claimed design. The broken line showing of a vertical seam in FIGS. 1, 2, 4, 6-8, 9, 10, 12, and 14-16, and of a surface ornamentation depicting a fire hydrant in FIGS. 1-6, 8, 9-14, 16, and 17 depicts portions of the attachment for a male dog housebreaking pad forming no part of the claimed design.
